METHOD OF AND APPARATUS FOR MAKING SHEET ICE

Filed Feb. 12, 1924

Patented Apr. 27, 1926.

1,582,158

UNITED STATES PATENT OFFICE.

GEORGE L. BENNETT, OF CLEVELAND HEIGHTS, OHIO.

METHOD OF AND APPARATUS FOR MAKING SHEET ICE.

Application filed February 12, 1924. Serial No. 692,221.

To all whom it may concern:

Be it known that I, GEORGE L. BENNETT, a citizen of the United States, residing at Cleveland Heights, in the county of Cuyahoga and State of Ohio, have invented certain new and useful Improvements in the Method of and Apparatus for Making Sheet Ice, of which the following is a specification, reference being had therein to the accompanying drawings, which form a part thereof.

My invention relates to a method and apparatus for making sheet ice and more particularly to a method and apparatus for this purpose, utilizing a slowly rotating drum immersed in water to be frozen and having a refrigerating medium circulating through the drum for the purpose of causing the formation of ice upon the perimeter of the drum.

The method and apparatus of my invention is particularly adapted for the production of sheets of ice to be broken into small pieces for use for various purposes where it is now required to break large cakes of ice into small pieces.

The production of the sheet ice and its handling, in the manner which will be hereinafter described, has the marked advantage that the time required to produce such sheets for a given bulk of broken ice is relatively much shorter than would be required in the formation of cake ice and its subsequent breakage into pieces of the desired size, thus introducing a large factor of economy in the production of the ice.

Furthermore, the method and apparatus of my invention is continuous in its operation and while the method requires the melting of one surface of the ice to facilitate its separation from the drum, the sheet of ice thus separated is subsequently subjected to a freezing temperature so as to "dry" the sheet before it is broken into small pieces and thus minimize likelihood of the amalgamation of the broken pieces before they have been finally delivered to the point of consumption.

Furthermore, by the method and apparatus of my invention, a plurality of similar sheets of ice may be simultaneously produced and the separate sheets thus formed may be bonded together during the "drying" stage of the method, thus permitting the production of a composite homogeneous sheet which will form larger pieces of

broken ice, and expedition in the production of said ice as a result of avoiding the necessity of accumulating ice of the desired maximum thickness upon a single drum. 60

The invention consists primarily in a method for making sheet ice, consisting in continuously forming a layer of ice in circular form by immersing and slowly rotating cylindrical body in water, while circulating a refrigerating medium within said body, stripping the layer of ice thus formed from said body in a continuous sheet, and thereafter passing this sheet through a refrigerator chamber to complete the congealing operation; and in such other novel steps and practices, and in the novel features of construction and combination of parts of the apparatus used for the practice of said method, all as hereinafter set forth 75 and described, and more particularly pointed out in the claims hereto appended.

Referring to the drawings,

Fig. 1 is a longitudinal section illustrating the method of my invention and the apparatus used for the practice of same; and

Fig. 2 is a transverse section through one of the units shown in Fig. 1, but upon a larger scale.

Like letters refer to like parts in both 85 of said views.

In the practice of the method or art of my invention, I employ a cylindrical closed body or drum, the lower portion of which is submerged in the water of which the ice 90 is to be formed, said water being distilled or otherwise conditioned in the usual manner to secure the desired purity of the product. This drum is slowly rotated and has a refrigerating medium in continuous circulation therethrough, so as to cause the water adjacent the perimeter of the cylinder or drum to congeal and adhere thereto. Formation of ice at the ends of this cylinder or drum is prevented, so as to limit the accumulation of the ice to upon the perimeter 100 thereof. The ice will form with considerable rapidity upon the drum, and the speed of rotation of the drum may be controlled so as to afford a time interval, during which 105 ice is being formed, commensurate with that required to produce ice of the desired thickness.

The ice thus formed upon the perimeter of the submerged portion of the cylinder or 110 drum will be of progressively increasing thickness to the point where the ice sheet

leaves the water, where it will have attained this maximum thickness.

After the portion of the drum and the ice thereon leaves the water in which it is immersed, the ice is stripped from the perimeter of the drum and passed to the point where it will be subjected to a temperature below the freezing point of the water, the thin sheet of ice having sufficient flexibility 10 to permit it to be thus led in a continuous sheet and passed through this low temperature zone. This will have the effect of completing the freezing operation, and effectively drying the sheet so that it may thereafter be broken up, there being no subsequent tendency of the pieces to adhere together in a manner to interfere with the desired looseness in the bulk of ice.

Since the surface of the ice formed directly against the metal of the cylinder or drum will tend to adhere in considerable tenacity to this surface, it is desired to subject the drum to a temperature sufficiently high to break this bond at a point substantially coincident with that at which the sheet is stripped from the drum. Hence, as a sheet of ice passes to the final low temperature zone, there will be a thin film of water upon one surface thereof, due to the melting 20 of the ice for breaking the bond, and possibly a thin film of uncongealed water upon the other surface thereof. The presence of these thin films makes the final treatment in the low temperature zone desirable, if not absolutely essential.

If it be desired to produce ice of a greater thickness than that which is secured by the above steps, I form two or more separate sheets of ice in the manner above described, and bring these sheets together in the final low temperature stage, so that the freezing 30 of the thin films of ice incidental to the drying of the sheets, will have the effect of bonding these two sheets into a single composite homogeneous strip of relatively greater thickness than either of the sheets forming the same. In fact, any desired number of such sheets may be thus collated or superimposed one upon the other and bonded together.

The apparatus which I preferably employ in the practice of the above described method, includes a tank *a* adapted to receive the distilled or otherwise purified water to be used in the making of the ice. This water is preferably maintained at a temperature approximately at, or slightly above, the freezing point of the water.

Mounted in relation to said tank *a*, so as 40 to cause the lower portion thereof to be immersed in the water within the tank, is a drum or drums *b* of metal of a thickness which will readily take up the heat from the water and transmit it to a refrigerating medium within the drum or drums. In this

manner, the heat units in the water will be absorbed with sufficient rapidity to rapidly form a layer of ice upon that portion of the drum immersed in the water in the tank *a*. Slow rotary movement is imparted to said 50 drum in any desired manner, as through a pulley *c*.

The ends of the drum are lined with heat insulating material *d* which will prevent a sufficiently rapid absorption of the heat units 55 from the water at the ends of the tank to cause the formation and accumulation of ice thereon.

The drum *b*, which is cylindrical in form, is rotatably mounted upon a hollow shaft *c* communicating with the interior of the drum through ports *e'*. Said shaft has an extension *e*² leading to the intake of a compressor now shown in the drawings.

Passing through this hollow shaft is a supply pipe *f* through which refrigerating medium, in liquid form, is delivered to within the lower part of the drum.

By this construction a constant circulation of ammonia or other refrigerating agent is maintained in the lower portion of the drum, which agent as it is volatilized or boiled out as a result of the absorption of heat units from the water being congealed, passes from within the drum through the hollow shaft *e*² to the compressor, or other devices for reconditioning these vapors to permit their continued use in the apparatus.

The hollow shaft *e* is provided with a vapor tight partition *g* limiting the flow of the vapor to one direction, and, at the same time, affording space for the introduction of a melting medium acting upon the drum, at a point to facilitate the stripping of the sheet of ice therefrom.

The shaft *e* is stationary and carries a transverse partition *h* within the drum, which partition is made of insulating material and has a close sliding fit within the drum and with the insulation *d* at the opposite ends thereof. This partition *h* prevents the vapors from the refrigerating medium entering the upper part of the drum, and permits the application of heat adjacent the surface of the drum above the partition at the point where the ice is to be stripped therefrom.

This heat is furnished through the coils *i* by means of the direct and return pipes *i'*—*i*² passing through the hollow shaft *e*, at one side of the partition *g* therein. To limit the application of heat to adjacent the point where the ice is to be stripped, I provide the partition *j*—*j'* about these coils. In this manner I get a localized action of the heat.

Bearing upon the drum adjacent the coils *i* is a stripper knife or doffer blade *k* and extending from adjacent said knife or blade are spaced guides or doffer guides *m* leading to the low temperature zone afforded by

the housing *n* containing the coils *o* through which a refrigerating medium is passed.

Intermediate the coils *o* are rollers *p*—*p'* adapted to assist in supporting the ice and apply pressure thereto, these rollers being arranged in pairs, the members of which are oppositely disposed. The lower guide or doffer guide *m* has an opening therethrough as shown, to permit the lower rollers *p'* to engage the ice through this guide or doffer guide.

Beyond the outlet of the housing forming the low temperature zone is a rotary breaker *q* which will break the ice into pieces as shown as they leave the low temperature zone and while the ice is firm and brittle. This manner of forming and breaking the ice will prevent the presence of very fine ice which quickly becomes slush, and as the ice is fairly dry, the broken ice may be readily handled, stored or packed without likelihood of its adhering and forming a mass which will be less efficient than a large cake of ice and difficult to handle at a temperature below 32° F.

In the form of the invention illustrated, I use the drum and the various parts appurtenant thereto, in duplicate, it being understood that by a mere change in the spacing of the pairs of rollers *p*—*p'*, the number of units may be increased, or merely one unit used when a thin ice sheet is desired.

However, since the time required to produce ice of varying thicknesses, varies disproportionately to that of the thickness of ice, great economy may be effected by the employment of a plurality of units.

It is apparent that from the time any portion of the perimeter of a drum passes the surface of the water in the tank *a* until the same portion of the drum leaves the water, ice will continue to be formed of progressively increasing thickness so that the thickness of the ice formed upon the drum in the tank will be of progressively increasing thickness to a point where it leaves the water.

It is also apparent that the ice formed upon the drum will have a tendency to adhere thereto with considerable tenacity so that so long as the surrounding atmosphere is maintained at a low temperature, which is common in the production of ice artificially, there is always likelihood of the chipping and breaking of the ice by the stripping knife or doffer blade unless the surface of the drum is subjected to a higher temperature before the ice meets this blade so as to break the bond between the ice and the drum sufficiently to facilitate a clean stripping of the ice sheet from the drum. It is desirable, however, to limit the area through which heat is applied to the drum, to as small a space as possible, to avoid the raising of the temperature of the drum to

a point where wastage will result from the necessity of again bringing it to a temperature sufficiently low to permit the rapid formation of ice thereon.

A thin sheet of ice has sufficient flexibility 70 to permit it to readily follow the guide plates or doffer guides *m*. As the sheet of ice is passing through or along this guide, both surfaces thereof will have a thin film of moisture thereon, which, however, will 75 be congealed as the sheet passes adjacent the coils *o*. When a plurality of sheets of ice are united to form a composite sheet of greater thickness, this film of moisture assists materially in forming the desired bond 80 between these sheets.

It will be observed that the apparatus will operate continuously while the drum is turned but very slowly. This continuous production of ice is much more economical 85 when the production of ice in cans, or even the production of plate ice and the subsequent breaking of this ice to reduce it to pieces of the size required.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. The herein described method of making sheet ice consisting in continuously 100 forming a layer of ice in curved form by immersing and slowly rotating a cylindrical body in water, while circulating a refrigerating medium within said body, stripping the layer of ice thus formed from said 105 body in a continuous sheet, and thereafter passing this sheet through a refrigerating chamber to complete the congealing operation.

2. The herein described method of making 110 sheet ice consisting in continuously forming a layer of ice in curved form by immersing and slowly rotating a cylindrical body in water, while circulating a refrigerating medium within said body, subjecting the layer 115 of ice while upon said body to a temperature which will break the bond between the ice and the body upon which it is formed, to facilitate the separation of the ice therefrom, stripping the layer of ice thus formed from said body in a continuous sheet, and thereafter passing this sheet through a refrigerating chamber to complete the congealing operation.

3. The herein described method of making 125 sheet ice consisting in simultaneously and continuously forming a plurality of layers of ice in curved form by immersing and slowly rotating cylindrical bodies in water while circulating a refrigerating medium in 130

each of said bodies, stripping each layer of ice thus formed from said body in a continuous sheet, and thereafter passing said sheets in surface contact one with the other 5 through a refrigerating chamber to complete the congealing operation and bond said sheets together.

4. The herein described method of making sheet ice consisting in simultaneously and 10 continuously forming a plurality of layers of ice in curved form by immersing and slowly rotating cylindrical bodies in water while circulating a refrigerating medium in each of said bodies, subjecting each layer of ice while upon the body upon which it is formed, to a temperature which will break the bond between the ice and the body upon which it is formed, to facilitate the separation 15 of the ice therefrom, stripping each 20 layer of ice thus formed from said body in a continuous sheet, and thereafter passing said sheets in surface contact one with the other through a refrigerating chamber to complete the congealing operation and bond 25 said sheets together.

5. The herein described method of making sheet ice consisting in simultaneously and continuously forming a plurality of layers of ice in curved form by immersing and 30 slowly rotating cylindrical bodies in water while circulating a refrigerating medium in each of said bodies, stripping each layer of ice thus formed from said body in a continuous sheet, thereafter passing said sheets 35 in surface contact one with the other through a refrigerating chamber to complete the congealing operation and bond said sheets together, and applying pressure to the sheets of ice while in said refrigerating chamber 40 to secure the desired intimate contact of the contacting surfaces thereof.

6. The herein described method of making sheet ice consisting in simultaneously and continuously forming a plurality of layers 45 of ice in curved form by immersing and slowly rotating cylindrical bodies in water while circulating a refrigerating medium in each of said bodies, subjecting each layer of ice while upon the body upon which it is formed, to a temperature which will break the bond between the ice and the body upon 50 which it is formed, to facilitate the separation of the ice therefrom, stripping each layer of ice thus formed from said body in a continuous sheet, thereafter passing said sheets 55 in surface contact one with the other through a refrigerating chamber to complete the congealing operation and bond said sheets together, and applying pressure to the sheets of ice while in said refrigerating chamber 60 to secure the desired intimate contact of the contacting surfaces thereof.

7. An apparatus for making sheet ice embodying therein a tank adapted to contain 65 water to be frozen, a drum mounted in said

tank in a position to cause a portion thereof to be immersed in the water contained in the tank, means whereby said drum may be slowly rotated, means whereby a refrigerating medium may be circulated through 70 said drum, a member adapted to bear upon said drum and strip therefrom the layer of ice formed thereon, a chamber, means whereby said chamber is maintained at a temperature which will congeal moisture upon the 75 surfaces of said sheet, and a guide supporting said sheet and extending from adjacent said member to within said chamber.

8. An apparatus for making sheet ice embodying therein a tank adapted to contain water to be frozen, a drum mounted in said tank in a position to cause a portion thereof to be immersed in the water contained in the tank, means whereby said drum may be slowly rotated, means whereby a refrigerating medium may be circulated through 80 said drum, a member adapted to bear upon said drum and strip therefrom the layer of ice formed thereon, a stationary heat-insulating partition adjacent the center of the 85 drum and said member, means whereby a portion of said drum above said partition is subjected to a temperature above the melting point of ice to break the bond between the ice and the drum, a chamber, means 90 whereby said chamber is maintained at a temperature which will congeal moisture upon the surfaces of said sheet, and a guide supporting said sheet and extending from adjacent said member to within said chamber. 100

9. An apparatus for making sheet ice embodying therein a tank adapted to contain water to be frozen, a drum mounted in said tank in a position to cause a portion thereof to be immersed in the water contained in the tank, means whereby said drum may be slowly rotated, means whereby a refrigerating medium may be circulated through said 105 drum, a member adapted to bear upon said drum and strip therefrom the layer of ice formed thereon, heat insulating means at opposite ends of said drum whereby the formation of ice is limited to the perimeter of said drum, a chamber, means whereby 110 said chamber is maintained at a temperature which will congeal moisture upon the surfaces of said sheet, and a guide supporting said sheet and extending from adjacent said member to within said chamber. 115

10. An apparatus for making sheet ice embodying therein a tank adapted to contain water to be frozen, a drum mounted in said tank in a position to cause a portion thereof to be immersed in the water contained in the tank, means whereby said drum may be slowly rotated, means whereby a refrigerating medium may be circulated through 120 said drum, a member adapted to bear upon said drum and strip therefrom 125

the layer of ice formed thereon, heat insulating means at opposite ends of said drum whereby the formation of ice is limited to the perimeter of said drum, a stationary 5 heat-insulating partition adjacent the center of the drum and said member, means whereby a portion of said drum above said partition is subjected to a temperature above the melting point of ice to break the bond between the ice and the drum, a chamber, 10 means whereby said chamber is maintained at a temperature which will congeal moisture upon the surfaces of said sheet, and a guide supporting said sheet and extending 15 from adjacent said member to within said chamber.

11. An apparatus for making sheet ice embodying therein a tank adapted to contain water to be frozen, a plurality of drums 20 mounted in said tank in a position to cause a portion thereof to be immersed in the water contained in the tank, means whereby said drums may be slowly rotated, means whereby a refrigerating medium may be 25 circulated through each drum, a member adapted to bear upon each drum and strip therefrom the layer of ice formed thereon, a chamber, means whereby said chamber is maintained at a temperature which will con- 30 geal moisture upon the surfaces of a sheet of ice, and guides extending from adjacent said members respectively to within said chamber with adjacent sheets in surface contact with each other, whereby the congealing 35 of moisture upon the contacting surfaces of said sheets will bond said sheets together.

12. An apparatus for making sheet ice embodying therein a tank adapted to contain water to be frozen, a plurality of drums 40 mounted in said tank in a position to cause a portion thereof to be immersed in the water contained in the tank, means whereby said drums may be slowly rotated, means whereby a refrigerating medium may be cir- 45 culated through each drum, a member adapted to bear upon each drum and strip therefrom the layer of ice formed thereon, a stationary heat-insulating partition adjacent the center of each of said drums and said 50 member operative upon that drum, means whereby a portion of each drum above said partition is subjected to a temperature above the melting point of ice between the ice and the drum, a chamber, means whereby said 55 chamber is maintained at a temperature which will congeal moisture upon the surfaces of a sheet of ice, and guides extending from adjacent said members respectively to within said chamber with adjacent sheets in 60 surface contact with each other, whereby the congealing of moisture upon the contacting surfaces of said sheets will bond said sheets together.

13. An apparatus for making sheet ice 65 embodying therein a tank adapted to con-

tain water to be frozen, a plurality of drums mounted in said tank in a position to cause a portion thereof to be immersed in the water contained in the tank, means whereby said drums may be slowly rotated, means 70 whereby a refrigerating medium may be circulated through each drum, each of said drums having heat insulating means at opposite ends thereof whereby the formation of ice is limited to the perimeter of the 75 drum, a member adapted to bear upon each drum and strip therefrom the layer of ice formed thereon, a chamber, means whereby said chamber is maintained at a temperature which will congeal moisture upon the surfaces of a sheet of ice, and guides extending from adjacent said members respectively to within said chamber with adjacent sheets in surface contact with each other, whereby the congealing of moisture upon the contacting 80 surfaces of said sheets will bond said sheets together.

14. An apparatus for making sheet ice embodying therein a tank adapted to contain water to be frozen, a plurality of drums 90 mounted in said tank in a position to cause a portion thereof to be immersed in the water contained in the tank, means whereby said drums may be slowly rotated, means whereby a refrigerating medium may be circulated through each drum, a member adapted to bear upon each drum and strip therefrom the layer of ice formed thereon, a chamber, means whereby said chamber is maintained at a temperature which will con- 95 geal moisture upon the surfaces of a sheet of ice, guides extending from adjacent said members respectively to within said chamber with adjacent sheets in surface contact with each other, whereby the congealing of moisture upon the contacting surfaces of said sheets will bond said sheets together.

15. An apparatus for making sheet ice 100 embodying therein a tank adapted to contain water to be frozen, a plurality of drums mounted in said tank in a position to cause a portion thereof to be immersed in the water contained in the tank, means whereby said drums may be slowly rotated, means whereby a refrigerating medium may be circulated through each drum, each of said drums having heat insulating means at opposite ends thereof whereby the formation of ice is limited to the perimeter of the 105 drum, a member adapted to bear upon each drum and strip therefrom the layer of ice formed thereon, a stationary heat insulating partition adjacent the center of each of said drums and said member operative upon that 110

115

120

125

130

- drum, means whereby a portion of each drum above said partition is subjected to a temperature above the melting point of ice between the ice and the drum, a chamber, 5 means whereby said chamber is maintained at a temperature which will congeal moisture upon the surfaces of a sheet of ice, and guides extending from adjacent said members respectively to within said chamber with 10 adjacent sheets in surface contact with each other, whereby the congealing of moisture upon the contacting surfaces of said sheets will bond said sheets together.
16. An apparatus for making sheet ice embodying therein a tank adapted to contain water to be frozen, a drum mounted in said tank in a position to cause a portion thereof to be immersed in the water contained in the tank, means whereby said 15 drum may be slowly rotated, means whereby a refrigerating medium may be circulated through said drum, a member adapted to bear upon said drum and strip therefrom the layer of ice formed thereon, a chamber, means whereby said chamber is maintained 20 at a temperature which will congeal moisture upon the surfaces of a sheet of ice, guides extending from adjacent said members respectively to within said chamber with adjacent sheets in surface contact with each 25 other, whereby the congealing of moisture upon the contacting surfaces of said sheets will bond said sheets together, and a breaker beyond said chamber adapted to break the sheet of ice as it emerges from the 30 chamber while it is still dry.
17. An apparatus for making sheet ice embodying therein a tank adapted to contain water to be frozen, a plurality of drums mounted in said tank in a position to cause a portion thereof to be immersed in the water contained in the tank, means whereby said drums may be slowly rotated, means 40 whereby a refrigerating medium may be circulated through each drum, each of said drums having heat insulating means at opposite ends thereof whereby the formation of ice is limited to the perimeter of the 45 drum, a member adapted to bear upon each drum and strip therefrom the layer of ice formed thereon, a stationary heat insulating partition adjacent the center of each of said drums and said member operative upon that 50 drum, means whereby a portion of each drum above said partition is subjected to a temperature above the melting point of ice between the ice and the drum, a chamber, means whereby said chamber is maintained 55 at a temperature which will congeal moisture upon the surfaces of a sheet of ice, guides extending from adjacent said members respectively to within said chamber with adjacent sheets in surface contact with each 60 other, whereby the congealing of moisture upon the contacting surfaces of said sheets will bond said sheets together, and a breaker beyond said chamber adapted to break the sheet of ice as it emerges from the 65 chamber while it is still dry.

In witness whereof I have hereunto affixed my signature, this 4th day of February, 1924.

GEORGE L. BENNETT.
